UNITED STATES PATENT OFFICE.

THOMAS W. WRIGHT, OF ANDERSON, INDIANA.

HANDLE

Application filed October 28, 1922. Serial No. 597,541.

To all whom it may concern:

Be it known that I, THOMAS W. WRIGHT, a citizen of the United States, and a resident of Anderson, county of Madison, and State of Indiana, have invented a certain new and useful Handle; and I do hereby declare that the following is a full, clear, and exact description thereof, reference being had to the accompanying drawings, in which like numerals refer to like parts.

This invention relates to improvements on handles for spades, shovels and other things, like the general type known as the D-handle and over what is set forth in former Letters Patent to me No. 710,389, granted September 30, 1902, and No. 801,623, patented October 10, 1905.

As stated in the last of said above mentioned patents, I found from experience certain serious difficulties in the handle as set forth in the first of said above patents, and the object of the second of said patents was to overcome some of those difficulties. One difficulty was the checking or cracking of the lower part of the D on both sides at the point where the handle or stem enters the D. That was sought to be overcome by the introduction of metal fasteners or brads 17.

I have found, however, great difficulty in preventing the cracking or checking of the D when made of wood, even with the brads in it, for while the brads would stay in place, the drying or changing of temperature would crack and check the wood so as to weaken and loosen the union between the D and the handle or stem, and so as to roughen the surface of the handle and splinter it sometimes and be injurious to the hand of the workman. Furthermore, the handle or stem at its upper end had to be so narrowed for insertion into the D in said former constructions, that it very greatly weakened the handle and caused the same often to break at the union between the D and the rest of the handle. This is shown in the prior specified patents where the reduced portion is flattened on both sides considerably. Furthermore, it has always been practically impossible to prevent the curved lower edges of the wooden D-handle from cracking and splintering so as to be very rough and dangerous to the hands. This occurs at the bend on each side of the lower part of the D-handle.

The object of the present invention is to overcome the difficulties above specified and other difficulties in such constructions and make the D-handle wholly or partly of metal so that the handle as a whole will be smooth, 60 strong and durable, and balanced substantially the same as the former types of handles, and which is necessary in the practical use of the handles.

The full nature of the invention will be understood from the accompanying drawings and the following description and claims.

In the drawings Fig. 1 is a plan view of the handle. Fig. 2 is a central longitudinal section through the same. Fig. 3 is an elevation of the upper end of the wooden handle or stem. Fig. 4 is a transverse section thereof on the line 4-4 of Fig. 3. Fig. 5 is an inside elevation of the upper 75 end of one of the sides of the metal D-handle, parts being broken away.

The handle construction shown in the drawings consists of a main handle or stem 10 made of wood, the body of the D 11 80 made of metal, and the grip 12 made of wood.

The main handle or stem 10 is made of wood and is round like ordinary handles for spades, shovels, forks and the like, and at its upper end it is reduced at 15 to form an annular shoulder, the reduced portion being cylindrical at its base and tapered and centrally cut out at 16 to form two similar prongs 17, each almost semi-cylindrical cross section, with flat inner faces separated by a V-shaped space at 16.

The body portion of the D-handle has a lower tubular round shank 18 adapted to receive and tightly surround the base of the reduced upper end of the main handle or stem 10, as shown in Fig. 2. The metal handle is bifurcated to form two side members 19, opposite each other and constituting the sides of the D. The lower part of each side member 19 is hollow or tubular so as to provide an elongated tapering recess at 20 which extends from the V 21 between the two recesses 20 about half way to the grip member 12, as shown in Fig. 2. The recesses 20 have an internal area to conform to and receive the prongs 17 on the upper end of the main handle or stem, and so that said wooden prong 17 will wedge tightly into the metal D-handle. Therefore, the 110

2
recesses 20 are of the same form in cross section as the prongs 17 shown in Fig. 4. The V 21 separating and connecting the two branches of the D-handle is relatively thick and strong, as shown in Fig. 2, for cooperating with the other parts of the D-handle and securely holding the same on the main handle or stem D.

In manufacturing this sort of handle, the wooden prongs 17 should be steamed or otherwise treated when the metal D is secured in place on the main handle 10 and afterwards permitted to dry and cure so that the wooden prongs 17 will, of their own accord, remain spread apart in the form and position shown in Fig. 2. This will hold the metal D-handle on the main stem or handle 10 securely, although glue may be used in addition for effecting a secure and permanent union between the two members.

The upper end of each side 19 of the metal D-handle is provided with a socket or recess 23 on the inside with a surrounding rib 24. This socket is preferably oblong, as shown in Fig. 5, and it is adapted to receive the reduced end 25 of the grip member 12 of the handle, as shown in Fig. 2. The reduced end 25 is shaped to fit snugly in the socket 23. A rivet 26 extends entirely through the grip member 12 and the two sides 19 of the metal D-handle, said two sides of the latter being provided with holes concentric with the sockets 23 for said rivet. The grip member 12 is preferably curved, as shown in Fig. 2, for comfort in handling, although the rivet 26 is straight. The oblong form of the sockets 23 and the ends of the grip member 12 prevent the latter from turning in the D-handle.

By making the D-handle of metal, a very strong and smooth handle is provided and comfortable to the workmen, and does not have splinters to injure them. In constructing said metal D-handle with the bifurcated recesses 20 in the two sides and uniting it with the main handle or stem 10 in the manner shown and described herein, and by making the grip 12 of wood, said metal D-handle is rendered relatively light for a metal handle, and yet amply strong, and thus its weight is so reduced that it successfully meets the requirement of balance necessary for comfortable use. By this is meant that the relative weights of the main handle or stem 10, and of the metal D-handle, are such as to practically balance each other in use, that is, neither end of the handle will be relatively heavier than the other, or at least neither end will be too heavy relative to the other end for comfortable use. The lower end of the D-handle is relatively thin, because it is made of metal, which enables the reduced upper end of the main handle or stem 10 to be larger and relatively stronger than when the D-handle is made of wood,

and it enables the base of the reduced portion to be cylindrical instead of flattened on each side, as is required with wood D-handles, because the wooden portion surrounding the reduced portion of the main handle or stem 70 must be relatively thick to prevent breaking, and that requires the reduced portion of the main handle or stem to be flattened on two sides, so that that part becomes relatively weak. This difficulty is overcome in the construction shown herein in Fig. 2.

While Fig. 2 shows the preferred construction, the invention is not limited to the details thereof, or to the relative dimensions of parts. The grip portion 12 can be made 80 of different shape and material from that shown and described, so far as this invention is concerned.

The main handle or stem and the prongs thereof are preferably made of wood, but 85 they may be made of any other suitable material that is capable of yieldingly wedging into the metal D-handle, as herein shown and described.

The invention claimed is:

1. A handle construction including a D-handle made of metal with the lower end and the lower portions of the two sides thereof hollow, and a main handle or stem formed with its upper end shaped to fit 95 tightly in the lower end of the D-handle and with prongs fitting tightly in the hollow portions of the sides of the D-handle.

2. A handle construction including a D-handle made of metal with the lower end 100 and the lower portions of the two sides thereof hollow, and a main handle or stem formed with its upper end shaped to fit tightly in the lower end of the D-handle and with prongs fitting tightly in the hollow portions of the sides of the D-handle, the lower end of said metal D-handle and the portion 105 of the main handle or stem therein being cylindrical in cross section.

3. A handle construction including a D-handle made of metal with the lower end and the lower portions of the two sides thereof hollow, and a main handle or stem formed with its upper end shaped to fit 110 tightly in the lower end of the D-handle and with prongs fitting tightly in the hollow portions of the sides of the D-handle, the lower end of said metal D-handle and the portion 115 of the main handle or stem therein being cylindrical in cross section, and the recesses in the sides of the D-handle and the prongs of the handle fitting therein being substantially semi-cylindrical in cross section.

4. A handle construction including a substantially V-shaped D-handle made of metal with the lower end and the lower portions of the two sides thereof hollow, and a main handle or stem formed with its upper end shaped to fit tightly in the lower end of the 120

D-handle and with prongs fitting tightly in the hollow portions of the sides of the D-handle.

5. A handle construction including a D-handle made of metal with the lower end and the lower portions of the two sides thereof hollow, the space between the sides of said metal handle being substantially V-shaped, and a main handle or stem formed with its upper end shaped to fit tightly in the lower end of the D-handle and with prongs fitting tightly in the hollow portions of the sides of the D-handle, the lower end of said metal D-handle and the portion of the main handle or stem therein being cylindrical in cross section, and the recesses in the sides of the D-handle and the prongs of the handle fitting therein being substantially semi-cylindrical in cross section.

6. A handle construction including a substantially V-shaped D-handle made of metal

with the lower end and the lower portions of the two sides thereof hollow, the sides of said D-handle being separated by a substantially V-shaped space, and a main handle or stem formed with its upper end shaped to fit tightly in the lower end of the D-handle and with prongs fitting tightly in the hollow portions of the sides of the D-handle.

7. A handle construction including a D-handle with the lower and side portions formed of metal with vertical elongated opposing sockets in the upper ends of the sides thereof and holes therein centrally of said sockets, a grip member formed with its ends vertically elongated to fit in said sockets, and a rivet extending through the sides of the metal portion of the D-handle and through said grip member.

In witness whereof, I have hereunto affixed my signature.

THOMAS W. WRIGHT.
